U.S. Appl. No. 29/387,947, Tinius.

Primary Examiner — Austin Murphy

(74) Attorney, Agent, or Firm — McGuireWoods LLP

(57) **CLAIM**

I claim the ornamental design for a chainsaw, as shown and described.

DESCRIPTION

FIG. 1 is a right-rear perspective view of the chainsaw;
FIG. 2 is a front view of the chainsaw shown in FIG. 1;
FIG. 3 is a rear view of the chainsaw shown in FIG. 1;
FIG. 4 is a right-side view of the chainsaw shown in FIG. 1;
FIG. 5 is a left-side view of the chainsaw shown in FIG. 1;
FIG. 6 is a top view of the chainsaw shown in FIG. 1; and,
FIG. 7 is a bottom view of the chainsaw shown in FIG. 1.
The subject matter shown in dashed lines, and any surfaces of
the design not shown, including interior surfaces, form no
part of the claimed invention.

1 Claim, 7 Drawing Sheets(56)
